UNITED STATES PATENT OFFICE.

SAMUEL WHINERY, OF EAST ORANGE, NEW JERSEY.

STREET CLEANING OR WASHING MACHINE.

1,191,489.

Specification of Letters Patent. Patented July 18, 1916.

Application filed July 30, 1915. Serial No. 42,713.

To all whom it may concern:

Be it known that I, SAMUEL WHINERY, citizen of the United States, residing at East Orange, in the county of Essex and 5 State of New Jersey, have invented certain new and useful Improvements in Street Cleaning or Washing Machines, of which the following is a specification.

My invention relates to improvements in 10 street cleaning or washing machines, of the type that embody squeegee elements.

An important object of the invention is to provide a machine of the above mentioned character, which is simple in construction, 15 inexpensive to manufacture, and convenient in use.

A further object of the invention is to provide means for supplying the water to the squeegee blades, in a novel manner, as they 20 slidably contact with the street to be cleaned, to render such cleaning continuous and expeditious.

Other objects and advantages of the invention will be apparent during the course 25 of the following description.

In the accompanying drawings forming a part of this specification and in which like numerals are employed to designate like parts throughout the same, Figure 1 is a 30 side elevation of a machine embodying my invention, Fig. 2 is a plan view of the same, with certain elements omitted, Fig. 3 is an enlarged plan view of a water supply branch pipe, Fig. 4 is a transverse sectional view 35 taken on line 4—4 of Fig. 3, Fig. 5 is a transverse sectional view through one of the squeegee blades, taken on line 5—5 of Fig. 2, Fig. 6 is a longitudinal sectional view taken on line 6—6 of Fig. 2, and, Fig. 7 is 40 a transverse sectional view taken on line 7—7 of Fig. 2.

In the drawings, wherein for the purpose of illustration is shown a preferred embodiment of my invention, the numeral 10 designates a wagon or wheeled vehicle as a 45 whole, comprising a water holding tank 11, arranged above and connected with axles 12 and 13. Arranged beneath the rear portion of the tank 11 and the rear axle 12 is a 50 vertically swinging squeegee blade frame or support 14, comprising longitudinal beams 15, which are preferably T-trails, as more clearly shown in Fig. 7. Arranged above the rear axle 12 are apertured plates 16, 55 receiving bolts 17, extending downwardly

upon opposite sides thereof for connection with depending brackets 18. These depending brackets have their vertical portions apertured for receiving horizontal bolts or pivot elements 19, passing through apertures 60 in the vertical webs of the beams 15, as shown. The brackets 18 are suitably spaced to receive the vertical portions of the beams 15 and packing elements or washers 20 may 65 preferably be arranged between these elements and apertured for receiving the bolts 19. Longitudinally adjustably mounted upon the forward ends of the beams 15 are weights 21, which are clamped thereto at desired positions by bolts 22 or the like. 70

As more clearly shown in Fig. 1, the forward portions of the beams 15 are substantially horizontal and these beams are provided with intermediate rearwardly inclined portions 23, carrying substantially horizontal rear portions 24, arranged in a horizontal plane spaced a substantial distance beneath the horizontal plane of the horizontal forward portions of the beams. Secured to the beams 15, at their rear horizontal portions 24, by means of bolts or the like, are transverse beams or L-irons or L-beams 25, which are inclined laterally with respect to the longitudinal axis of the machine and are suitably spaced. As more clearly shown in 80 Fig. 5, each L-beam 25 has a squeegee blade 26 arranged in advance thereof and attached thereto by bolts 27 or the like. These squeegee blades are preferably flexible and may be formed of leather, rubber, or other suitable material. 85

Arranged adjacent the forward ends of the transversely inclined squeegee blades is a water supply pipe 28, arranged above and extending transversely of them. This pipe 28 may be bolted or otherwise rigidly attached to the beams 25. The pipe 28 is provided with a coupling 29, between its ends, for connection with a preferably flexible hose or conduit 30, extending upwardly for 95 connection with a pipe 31. This pipe 31 communicates with the interior of the tank 11, at its bottom, and is preferably provided with a manually operated cut-off valve 32. The pipe 28 is provided with vertical depending discharge pipes 32', arranged between the squeegee blades adjacent their forward ends. As clearly shown in Fig. 3, one of the pipes 32' is arranged forwardly 100 of the forward end of each squeegee blade, 110

and is provided with a manually operated cut-off valve 33. Means are provided to swing the rear end of the frame 14 upwardly, to elevate the squeegee blades out 5 of contact with the street, comprising a vertically swinging lever 34, arranged above the rear end of each beam 15. Connected with these levers are flexible elements or chains 35, extending downwardly for connection with the horizontal portions 24 of 10 the beams 15. The levers 34 are rigidly mounted upon a rock-shaft 36, journaled through the ends of horizontal beams 37, suitably attached to the tank 11. This rock-shaft is turned by an upstanding crank 38, having pivotal connection with a rod 39, 15 pivotally connected with a hand lever 40. This lever is pivoted at 41 and is equipped with latch means 42 to coöperate with a stationary toothed segment 43, whereby the lever may be locked in adjustment at the desired position.

The operation of the machine is as follows: The longitudinal travel of the machine in the forward direction may be effected by means of draft animals or the like. The lever 40 is swung rearwardly to lower the frame 14 and place the squeegee blades 26 in slidable contact with the street. The 20 valves 33 being adjusted or opened the water is supplied from the tank 11 to points forwardly of and adjacent the forward ends of the transversely inclined squeegee blades. The water is thus made to travel from one 25 end of the squeegee blades to the other, before discharging from their rear ends. During the slidable contact of the squeegee blades with the street, the beams 15 being pivotally supported and counter-weighted 30 by the weights 21, such squeegee blades may rise and fall with respect to the tank 11, to conform to the curvature or surface of the street.

It is to be understood that the invention 45 is in no sense restricted to the specific means for introducing the water in advance of the squeegee blade or blades. Instead of introducing the water adjacent the forward end of the blade, in front of it, such water may 50 be fed in advance of the blade at any other desired point between its ends or the water

may be fed in advance of the blade throughout its entire length.

It is to be understood that the form of my invention herewith shown and described is 55 to be taken as a preferred example of the same, and that various changes in the shape, size, and arrangement of parts may be resorted to without departing from the spirit of the invention or the scope of the sub- 60 joined claims.

Having thus described the invention, I claim:—

1. A street washing and cleaning machine, comprising a wheeled frame, a water tank 65 thereon, a vertically movable frame connected with the wheeled frame, means for detachably securing said vertically-movable frame in raised position, squeegee blades connected with said frame and arranged one 70 in front of the other in spaced relation, a conduit mounted on said frame and disposed above the squeegee blades and having discharges disposed forwardly of and adjacent to said blades, and a flexible conduit intermediate said conduit on the vertically-movable frame and the water tank. 75

2. A street washing and cleaning machine, comprising a wheeled frame, a water tank thereon, a vertically swinging frame 80 arranged below and longitudinally of said wheeled frame and pivotally connected at an intermediate point of its length thereto, counter-balancing means on the forward portion of said vertically-swinging frame, 85 means for detachably securing the rear portion of said frame in raised position, squeegee blades connected with said rear portion of the frame and arranged one in front of the other in spaced relation, a conduit mounted on said rear frame portion and disposed above the blades and having discharges disposed forwardly of and adjacent to the blades, and a flexible conduit intermediate said conduit on the rear frame 90 portion and the water tank. 95

In testimony whereof I affix my signature in presence of two witnesses.

SAMUEL WHINERY.
